(57) **CLAIM**

The ornamental design for an air filtration device, as shown.

DESCRIPTION

FIG. 1 is an overall perspective view of an air filtration device;

FIG. 2 is a front elevational view thereof;

FIG. 3 is a left side elevational view thereof;

FIG. 4 is a right side view thereof;

FIG. 5 is a rear view thereof;

FIG. 6 is a top plan view thereof; and,

FIG. 7 is a bottom plan view thereof.

The broken line showing is included for the purpose of illustrating and forms no part of the claimed design.
